CLAIM

The ornamental design for an eye speculum as shown and described.

DESCRIPTION

FIG. 1 is a front perspective view of the eye speculum showing my new design;

FIG. 2 is a second front perspective view thereof;

FIG. 3 is a third rear perspective view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a right-side elevation view thereof; and,

FIG. 9 is a left-side elevation view thereof.

The broken lines in the figures represent portions of the eye speculum that form no part of the claimed design.

1 Claim, 7 Drawing Sheets
